COMPOUND TOOL

James J. Plumb, Spokane, Wash.

Application April 15, 1935, Serial No. 16,394

9 Claims. (Cl. 33—102)

This invention relates to a combination tool of the type used by carpenters and other mechanics and one object of the invention is to provide a compact tool of such construction that it may be used as a tri-square, miter square, a plumb or as a level.

Another object of the invention is to provide a compound tool including a handle or body and a blade which is so connected with the body that it may be angularly adjusted relative thereto and firmly but releasably secured in an adjusted position.

Another object of the invention is to so construct the body that the blade may be disposed transversely thereof in any desired angular relation to the handle when in use and when not in use disposed longitudinally of the handle in close fitting relation thereto where it will be partially encased by the body and when in this folded position fit easily into a pocket.

Another object of the invention is to provide improved means for securely holding a protractor disc in a set position and at the same time allow a latch for the disc to be easily moved to a releasing position and held in the releasing position if so desired.

Another object of the invention is to provide a blade and blade holding discs which have such cooperation with each other that when a set screw engaging one of the discs is manipulated, the disc may be shifted into or out of position to cause a firm gripping action to take place between the blade and discs.

The invention is illustrated in the accompanying drawing, wherein

Figure 1 is a perspective view of the compound tool.

Figure 2 is a section taken longitudinally through the body along the line 2—2 of Figure 1.

Figure 3 is a section taken along the line 3—3 of Figure 2.

This improved tool consists briefly of a blade 1 in the form of a steel ruler and a handle or body 2 formed of strong metal and having upper and lower sections 3 and 4. The blade 1 is disposed between the sections of the handle and engaged by securing means which firmly holds the blade and retains it in desired angular relation to the handle. When the tool is not in use, the blade is disposed longitudinally of the handle at one side thereof, as shown in dotted lines in Figure 3, and thus reduce the device to a compact mass and permit it to be easily carried in a pocket.

The two sections of the handle are rectangular in shape and adjacent one end of the handle each

section is formed with a circular socket, the socket 5 of the section 3 being of a depth less than the thickness of the section and having a groove 6 about its periphery which is V-shaped in cross section. A bore 7 leads from the center of the socket 5 through the outer face of the section and about this bore, the outer face of the section is recessed to form concentric surfaces 8 and 9. The socket 10 of the section 4 extends entirely through the section but its inner end portion is reduced in diameter, thereby forming an annular shoulder so that when the discs 11 and 12 are in place the outstanding marginal flange of the disc 12 will have a surface to bear against. The disc 11 carries a marginal rib 13 which fits into the groove or seat 6 and permits this disc to rotate while preventing transverse shifting thereof. The hub 14 of the disc 11 is journaled through the bore 7 and has a tapered outer end portion about which fits the conical central portion of a dial 15 which is firmly held in place by the large flat head of a screw 16, the stem of which is screwed into a socket formed in the hub of the disc 11. By this arrangement the dial and disc 11 will turn as a unit and since the disc 12 is formed with openings 17 through which screws 18 pass, the disc 12 will turn with the disc 11. The openings through which the screws 18 pass are elongated radially of the disc and, therefore, the disc 12 may be shifted diametrically of the socket 10.

In order to close the socket 10 there is provided a cap or disc 19 carrying a cover plate 20 which is square instead of circular and, therefore, its corner portions project from the cap, as indicated by dotted lines in Figure 3, and overlap the outer face of the section 4 so that screws 21 may be passed through these corner portions of the cover plate and securely hold the cover plate and cap in place. Registering openings, which are threaded, are formed through the cap and cover plate centrally thereof to receive an adjusting screw 22 having a conical spur or cam 23 at its inner end which is adapted to engage in a conical recess or seat 24 formed in the outer face of the disc 12 and set up a cam action when the screw is turned inwardly which will cause the disc 12 to be shifted toward the right in Figure 2. Grooves 25 and 26 are formed in confronting faces of the discs 11 and 12 to receive the marginal portion along the back of the blade or ruler 1, the groove 26 extending across the disc 12, as shown in Figure 3, and defining a rib 27 which engages in a groove 28 formed in the blade. The blade will, therefore, be in interlocked engagement with the discs and, when the set screw 22

- is loosened, may be slid longitudinally and caused to project a desired distance from opposite sides or ends of the handle. When the set screw is tightened, the disc 12 will be shifted toward the right in Figure 3 thus causing the rib 27 to be shifted toward the rear edge of the blade and creating a tight binding grip upon the blade which will securely hold the blade in a set position.
- 10 A rib 29 extends longitudinally of the inner face of the handle section 3 between the socket 6 and the rear end of the section and when the handle section 7 is secured against this rib by the screws 30, marginal portions of the two sections at the front end of the handle and along opposite sides thereof will be held in spaced relation to each other and thus permit the blade to extend transversely of the handle with a portion engaged between the sections or longitudinally 15 of the handle at a selected side thereof with a portion of the blade engaged between the sections as shown in dotted lines in Figure 3. It will thus be seen that by properly adjusting the discs, the blade may be caused to extend in desired angular 20 relation to the front edge or a side edge of the handle and the tool may be used as a tri-square, a miter square when laying off risers for steps or the like, or merely as a handle for conveniently holding the ruler.
- 25 The angle at which the blade or ruler extends relative to the handle is determined through the medium of the dial 15 and referring to Figure 1 it will be seen that this dial is formed about its margin with notches 31 which are spaced from 30 each other circumferentially of the dial and are marked to indicate degrees of a circle. A latch 32 is pivotally mounted in a groove or pocket 33 formed in the outer face of the handle section 3 by a pin 34 and yieldably held in position for 35 its front end to enter a notch of the dial by a spring 35 which extends longitudinally in the pocket where it is secured at its rear end and has its front end engaged under the rear end of the latch. An opening 36 is formed near the rear 40 end of the latch to receive the shank 37 of a button 38 and upon referring to Figure 2 it will be seen that the shank is slidably and rotatably received in a well 39 formed in the rib 29. A head 45 40 in the form of an incomplete circular flange is formed at the lower end of the shank 37 so that when the latch is moved to a releasing position by pressure applied to the button, the button may be rotated a sufficient distance to move a portion of the head under the shoulder 41 formed 50 by the enlarged portion of the well and thus cause the latch to be securely but releasably held in a releasing position. After the dial has been turned to dispose the blade or ruler in the desired angular 55 relation to the handle, the latch will be released and the spring will move it into a notch of the dial where it will serve very effectively to prevent 60 rotation of the dial and discs and, consequently, the blade cannot move out of an adjusted position.
- 65 The device is to be used as a plumb and also as a level and, therefore, the rear end portion of the handle is formed with a passage consisting of registering openings 42 and 43 formed through the handle sections. These openings are rectangular in shape and walls of the opening 42 are recessed, as shown at 44, to provide seats which are arcuate in cross section. Bubble glasses 45 are seated in the recesses 44 where they are held by a sheet metal frame 46 which fits about 70 75 the glasses and is held in place by screws 47 passed through openings formed in corner sections of the frame which overlap the handle sections. The usual sight openings 48 are formed in the frame to expose intermediate portions of the bubble glasses and permit their bubbles to be seen when the device is used as a level or plumb. It will be understood that when the device is used as a level or plumb the blade will be either removed or disposed at a side of the handle where it will be parallel thereto and used as an extension, thus adding to the bearing surface.
- Having thus described the invention, what is claimed as new is:
1. A compound tool comprising a handle consisting of upper and lower companion sections 15 formed with registering openings defining a socket opening through the bottom of the handle and having a bore leading centrally therefrom through the top of the handle, sides of the handle and the adjacent end thereof being formed with slots 20 communicating with the socket, a disc rotatable in the opening of the top section and having a hub rotatably received in the bore, a dial secured to the outer end of said hub, a second disc rotatably received in the opening of the lower handle 25 section and formed with a conical recess at its center and with openings at opposite sides of the recess elongated radially of the disc, opposed grooves formed in marginal portions of confronting faces of said discs, the groove of one disc 30 defining a rib, a blade slidably received in the slotted portions of said handle with its rear edge portion engaged in the grooves of said discs and formed with a longitudinally extending groove receiving the rib of the disc, screws carried by 35 the upper disc and engaged through the openings of the lower disc, a cap for the socket carried by lower disc and formed with an opening registering with the center recess of lower disc, a set screw threaded through the opening of said 40 cap and having a conical extension at its inner end engaged in the conical recess for shifting the lower disc and causing binding engagement between its rib and the blade when the set screw is turned inwardly, and means for engaging said 45 dial and releasably holding the dial and discs in a set position with the blade extending in predetermined angular relation to the handle.
2. A compound tool comprising a handle having a socket adjacent one end and an opening 50 adjacent its other end, a pocket being formed longitudinally of the handle between the socket and opening, the handle being grooved along its sides and across one end with the end groove and adjoining end portions of the side grooves opening into the socket, a passage leading from the socket centrally thereof, discs rotatably mounted in said socket, one disc having a shank rotatably engaged through the passage and the other disc being loosely held in engagement with the first 55 disc and slidably diametrically thereof, confronting faces of the discs being recessed to form a seat and rib, a blade slidably longitudinally through said seat and formed with a groove receiving said rib, the second disc being formed 60 with a central cam surface, a cap closing the open end of said pocket, an adjusting screw threaded through said cap and having a cam at its inner end for engaging the cam surface of the disc and shifting the disc to effect grip upon 65 the blade and secure the blade in a set position in predetermined angular relation to the handle with portions extending through grooves of the handle, a protractor disc carried by the outer end of said shank, a latch movably mounted in said 70 75

5 pocket and yieldably held in position to engage said protractor disc and hold the discs against rotation, bubble glasses fitting against walls of the opening in the handle, and a frame secured in the opening with portions engaging about the bubble glasses and formed with cut-outs exposing portions of the glasses.

10 3. A tool of the character described comprising a handle formed with a socket having a bore leading centrally therefrom and having its sides and front end formed with grooves opening into the socket, a marginal recess being formed in the socket, inner and outer discs rotatably mounted in said socket, the inner disc having a shank rotatably engaged through the bore and a marginal rib engaged in the recess, the outer disc being rotatable diametrically of the inner disc and turning with the inner disc, a seat being formed between confronting faces of said discs, a blade 15 rotatable longitudinally through said seat and having movement in the grooves of the handle when the discs are rotated to dispose the blade in adjusted angular relation to the handle, a cap for said socket, an adjusting screw threaded through said cap and at its inner end having a cam portion engaging a companion portion of the outer disc to shift the disc into gripping engagement with the blade when the screw is turned inwardly, a dial carried by the outer end of said shank, and 20 a latch movably carried by said handle and yieldably held in position to engage and secure the dial and discs in a set position.

25 4. A tool of the character described comprising a handle formed with a socket and a pocket adjacent the socket, inner and outer discs rotatably mounted in said socket and having confronting faces formed with a seat, a blade rotatable through said seat and movable with the discs to an angularly adjusted position relative to the handle, the outer disc being rotatable diametrically of the inner disc into position to cause the blade to be gripped in the seat and held against movement relative to the discs, a cap for the socket, a screw threaded through the cap and engaging 30 the outer disc to shift the same to a gripping position when the screw is turned inwardly, a dial carried by the inner disc externally of the handle, a latch pivoted in said pocket and yieldably held in position to engage and secure the dial, and 35 means for moving the latch out of engagement with the dial and releasably holding the latch in an inoperative position.

40 5. A tool of the character described comprising a handle formed with a socket and a marginal slot opening into the socket, inner and outer discs rotatably mounted in said socket and having confronting faces formed with a seat communicating with the marginal slot of the handle, the outer disc being rotatable diametrically of the 45 inner disc and turning with the inner disc, a cam surface being formed centrally of the outer disc, a cap for said socket, a blade engaged through the seat and marginal slot of the handle, a screw threaded through said cap and having a cam element at its inner end for engaging the cam surface and shifting the outer disc into position to grip the blade when the screw is turned inwardly, a dial carried by the inner disc and disposed externally of the handle, and a latch carried by the handle and movable into and out of 50 position to engage said dial and secure the discs.

55 6. A tool of the character described comprising

ing a handle, a pair of discs rotatably carried by said handle, one disc being shiftable transversely of the other and having its outer face formed with an inwardly tapered recess, a blade rotatable between said discs and moving with the discs 5 to angularly adjusted positions relative to the handle when the discs are rotated, a screw having a cam portion for engaging in the recess and shifting the disc to a position to grip the blade when the screw is turned inwardly, and means 10 for releasably holding the discs against rotation with the blade at a predetermined angle relative to the handle.

15 7. A tool of the character described comprising a handle, opposed discs rotatably carried by said handle, a blade rotatable longitudinally between said discs and movable with the discs to angularly adjusted positions relative to the handle, one disc being shiftable transversely of both the blade and the other disc and adapted to 20 grip the blade and secure the blade in an adjusted position when shifted in one direction, means carried by the handle for releasably securing the shiftable disc in position to grip the blade and prevent longitudinal sliding of the 25 blade also serving as means for shifting the disc to a gripping position, a dial carried by the other disc, and a latch movable into and out of position to engage said dial and hold the dial and discs against rotation with the blade in desired 30 angular relation to the handle.

35 8. A tool of the character described comprising a handle, discs carried by said handle and rotatable together relative thereto, a blade rotatable longitudinally between said discs with portions projecting from the handle, one disc being shiftable into and out of position to grip the blade and secure the blade against sliding, means for shifting the said disc to a gripping position and securing the same in the gripping position, a dial 40 carried by the other disc externally of the handle, a pocket being formed in said handle adjacent said dial, a well leading from said pocket, a latch pivotally mounted in said pocket and having an opening over the well, a spring yieldably holding 45 the latch in an operative position for engaging the dial and securing the dial and discs against rotation, and an actuating button for the latch having a shank slidably engaged through the opening of the latch and extending into the well 50 and having an abutment for engaging a shoulder in the well and releasably holding the button in a depressed position with the latch out of engagement with said dial.

55 9. A tool of the character described comprising a handle, a blade, blade-holding means rotatably carried by said handle, a dial carried by and rotating with the blade-holding means, a pocket being formed in the handle adjacent the dial and the handle being formed with an opening 60 leading from the pocket and having a shoulder intermediate its depth, a latch in the pocket pivotally mounted and yieldably held in position to engage the dial, and a button carried by said latch and having a shank slidably received in the well 65 and rotatable therein and formed with a flange movable into position to engage under the shoulder and hold the latch out of engagement with the dial when the button is pressed upon and 70 turned in the well.

JAMES J. PLUMB.
